Primary Examiner—Horace B. Fay, Jr.
Attorney, Agent, or Firm—Juliana Agon**[57]****CLAIM**

The ornamental design for a housing for a personal cordless telephone, as shown and described.

DESCRIPTION

FIG. 1 is a front elevational view of a personal cordless telephone showing our new design in open position;
FIG. 2 is a top plan view thereof;
FIG. 3 is a rear elevational view thereof;
FIG. 4 is a bottom plan view thereof;
FIG. 5 and 6 are respectively left and right side elevational views thereof in $\frac{1}{2}$ open position; and,
FIG. 7 is a front, top and right side perspective view thereof in half open position.

*FIG.1**FIG.2*

*FIG. 3**FIG. 4*

*FIG.5**FIG.6**FIG. 7*
